APPARATUS FOR COLD ROLLING AXLE JOURNALS

William L. Scribner and Tracy V. Buckwalter,
Canton, Ohio, assignors to The Timken Roller
Bearing Company, Canton, Ohio, a corporation
of Ohio

Application June 6, 1936, Serial No. 83,940

4 Claims. (Cl. 80—22)

The service conditions that affect locomotive and railway car axles are such that the journal portions thereof are liable to fail through fatigue; and it has been found that the capacity of the axle for reducing fatigue can be greatly increased by suitably cold rolling the journals thereof. The principal object of the present invention is to devise an apparatus for cold rolling such journals and particularly to devise means for insuring the proper pressure of the rollers on the journals and means to facilitate the positioning of the journals with relation to the rolling apparatus. The invention consists in the parts and in the combinations and arrangements of parts hereinafter described and claimed.

In the accompanying drawings wherein like reference numerals refer to like parts wherever they occur,

Fig. 1 is a plan view of an axle journal rolling device embodying our invention;

Fig. 2 is a side elevation of said device;

Fig. 3 is an end elevation of said device;

Fig. 4 is a vertical section on the line 4—4 in Fig. 3;

Fig. 5 is a vertical section on the line 5—5 in Fig. 2;

Fig. 6 is a plan view of a lever for supporting the upper roller of the rolling device; and

Fig. 7 is a plan view of the latch member of the device with the yoke for supporting the upper roller positioned therein.

The framework of the device illustrated in the drawings comprises two C-shaped members 1 open at the top. These members have matching ribs 2 on their inner faces which abut against each other and serve to space apart the main portions of said members. Said members are secured together by bolts 3 that pass through holes provided therefor in said ribs.

Located between the frame members at each of the lower corners of said frame is a work roller 4 which is rotatably mounted on a bearing bushing 5 or other bearing on a horizontal pin 6 provided therefor in said frame members. The peripheral surfaces of the work rollers are convex longitudinally of the axes thereof.

At the top of one side of the frame is pivotally mounted a member that is hereinafter called the throat latch 7. This member is pivotally mounted on a bolt or pin 8 that extends through bores provided therefor in said frame members and is held in place by a nut 9 working on the threaded end of said bolt. This throat latch extends across and beyond the open end of the frame and is provided with a horizontal bore in position to

register with bores in the top portion of the other side of the frame. The throat latch is locked in position by means of a pin 10 that fits accurately in said bores but is easily withdrawable therefrom.

The middle portion of the throat latch has an opening 11 extending vertically therethrough and its vertical sides are finished to constitute a slide-way for a yoke 12 or bifurcated block. In the downwardly extending arms of this yoke is mounted a pin 13 on which is a roller bearing or a bushing 14 that serves as a bearing for a work roller 15. By this arrangement, the yoke, together with the roller rotatably mounted therein, is capable of sliding up and down in the slide-way in the throat latch.

The throat latch is extended beyond the framework and its projecting portion has a rod 16 welded, screwed or otherwise securely fastened thereto in a substantially vertical position. On top of the throat latch near one end thereof is a pair of spaced lugs 17, each of which has a horizontal threaded bore extending through it. In each bore is mounted a cap screw 18 whose inner end enters a bore provided therefor in the end portion of a lever 19, the two pins constituting the pivot or fulcrum of said lever. This lever extends horizontally above the throat latch and has a vertical hole 20 through its end portion of suitable size and in proper position for the rod 16 to extend through freely. The rod extends upwardly through said hole and has its end portion screw-threaded and provided with a nut 21 and washer 22. Between the washer and the end portion of the lever 19 is a heavy helical spring 23 that surrounds said rod.

The middle portion of the lever has an opening 24 extending vertically therethrough into which extends the reduced top portion 25 of the yoke 12. Each side of this vertical extension of the yoke has a threaded socket 26 in which works the inner end of a cap screw 27 that extends through the adjacent side of the lever.

On one side of the frame is attached a horizontal stem or shank 28 that is adapted to fit in a socket in the tool post of an engine lathe (not shown) of ordinary type wherein the tool post has a feed movement.

The operation of the device hereinbefore described is as follows: Assuming that the shank 28 is mounted in the tool post of the lathe, its throat latch is swung on its pivot 8 to open the throat, and the axle to be rolled is passed through said throat and mounted with its ends centered on the head and tail stocks of the lathe. The throat

latch, with its spring 23 slackened, is then swung back into closed position, with the rollers against the journal of the axle, and locked by means of the locking pin 10. The lathe is then started so as to rotate the axle and feed the rolling device lengthwise thereof. The slack nut 21 on the end of the spring rod 16 is then tightened gradually until the spring exerts the desired pressure on the end of the lever. When the longitudinal feed 10 of the rollers carries them to a predetermined point, the nut 21 is gradually slackened to ease the spring pressure to zero or thereabouts before the lathe is stopped. Then the locking pin 10 is withdrawn, the throat latch is swung open 15 and the axle removed. The pressure of the throat latch roller (and of the other work rollers) against the axle journal is, of course, greater than the pressure of the spring in the proportion that the length of the lever is greater than the 20 distance of its point of application to the rollers from the pivot point.

The effect of the rolling with a suitable pressure of, say, about seventeen to twenty-one thousand pounds per roller for axles of from about eight to ten inches in diameter, is not merely to smooth and burnish the surface of the journal but to greatly improve the capacity of said journal for resisting fatigue.

30 While the device hereinbefore described is especially useful in increasing the fatigue strength of railway car and locomotive axles, it is applicable also to axles and shafts generally.

What we claim is:

35 1. An apparatus for cold rolling axle journals and the like, which comprises a C-shaped frame having a pivoted throat latch across its open top side, longitudinally convex rollers in its lower corners, a lever pivotally mounted on said throat latch, a yoke vertically slidable on said throat latch and operatively connected to said lever to be movable therewith, a roller mounted in said yoke in staggered relation to said first mentioned rollers and means for exerting pressure on said lever, said means comprising a threaded rod on the end portion of said throat latch extending transversely beyond said lever and having a nut thereon and a helical spring bearing against said nut and said lever, and means for detachably locking said throat latch in position, said locking

40

45

means consisting of an easily withdrawable locking pin extending through said throat latch and fitting in bores in the frame.

2. An apparatus for cold rolling axle journals and the like which comprises a C-shaped frame having a pivoted throat latch across its open side, and also having bores adapted to receive a locking pin, means for locking said throat latch in closed position, longitudinally convex rollers in two of the corners of the frame, a like roller slidably mounted on said throat latch in staggered relation to said first mentioned rollers, and means for exerting pressure radially on said slideable roller while the throat latch is locked, the throat locking means comprising a withdrawable locking pin fitting said bores in the frame. 1

3. An apparatus for cold rolling axle journals and the like which comprises a C-shaped frame having a pivoted throat latch across its open top side with a bifurcated end which has aligned bores adapted to receive a locking pin, means for detachably locking the free end of said latch, said means comprising a withdrawable locking pin fitting said bores in the ends of said frame, longitudinally convex rollers in the corners of said frame, a lever pivotally mounted on said throat latch, a yoke vertically slidable on said throat latch and operatively connected to said lever to be movable therewith, a roller mounted in said yoke, in staggered relation to said first mentioned rollers and means for exerting pressure on said lever. 2 30

4. An apparatus for cold rolling axle journals and the like which comprises a C-shaped frame, a throat latch extending across the open side of the frame and having one end pivotally mounted on said frame, easily withdrawable means for locking the other end of said throat latch to said frame, longitudinally convex rollers in the closed corners of said frame, a lever pivotally mounted on said throat latch, a yoke slidable on said throat latch and operatively connected to said lever to be movable therewith, a roller mounted in said yoke, in staggered relation to said first mentioned rollers and means for exerting pressure on said lever, said pressure means being independent of said locking means.
